UNITED STATES PATENT OFFICE

147,008

DESIGN FOR A HANDBAG

Elizabeth N. Graham, New York, N. Y.

Application March 10, 1947, Serial No. 137,477

Term of patent 14 years

(Cl. D87—3)

To all whom it may concern:

Be it known that I, Elizabeth N. Graham, a citizen of the United States of America, residing in New York city, county of New York, and State of New York, have invented a new, original, and ornamental Design for a Handbag, of which the following is a specification, reference being had to the accompanying drawing, forming part thereof, wherein

Figure 1 is a front elevational view of a handbag showing my new design.

Figure 2 is an end elevational view.

Figure 3 is a top plan view showing the handbag in open position with the handle partly broken away for convenience of illustration.

The rear of the handbag is substantially the same in appearance as the front, except for the omission of the handle closure and drawstring strap closure.

I claim:

The ornamental design for a handbag, substantially as shown and described.

ELIZABETH N. GRAHAM.
